ELECTRONIC TRANSLATING DEVICE

Herbert Ziebolz, Chicago, Ill., assignor, by mesne assignments, to Electronbeam, Ltd., Chicago, Ill., a partnership of Illinois

Application December 22, 1941, Serial No. 424,059

5 Claims. (Cl. 315—21)

The invention relates to an electronic translating device of the cathode-ray tube type for relaying, amplifying, converting, transforming or otherwise translating electrical, magnetic or electromagnetic signals, or signals of any nature which may be converted by known means into electric, magnetic or electromagnetic signals. The invention is useful in translating signals representing physical, chemical or other conditions, such as chemical reactions, heat, sound, light, mechanical motion or displacement which may be converted by such means as thermocouples, microphones, light sensitive cells, mechanical movements or displacements of magnets, charged bodies, electromagnets, coils or cores of electromagnets.

One object of the invention is to provide means for performing these translating functions with a minimum of distortion due to any change in the characteristics of the means or of the electronic device.

Another object of the invention is to provide a translating device for performing these functions without reflecting any variation from the controlled means back into the signal source.

Another object of the invention is to provide means by which mechanical, electrical, magnetic and electromagnetic signals may be converted from one type into another with a minimum of distortion due to changes in the characteristics of the converting means.

Another object of the invention is to provide means by which mechanical, electrical, magnetic, electromagnetic signals may be amplified or proportioned with a minimum of influence of changes in the characteristics of the amplifying means.

Another object is to provide an electronic device of this character which can be employed as a direct current amplifier.

The invention disclosed herein is related to the invention disclosed in copending application Ser. No. 417,871, filed November 4, 1941 (Patent No. 2,314,302), and the arrangements described in the present application are modifications of the invention disclosed in the earlier application.

In the earlier application Ser. No. 417,871, the electron stream or beam of a cathode-ray tube is deflected by suitable deflecting means to vary the number of electrons intercepted by electron receiving means or an anode, the deflecting means being energized in accordance with signals to be translated. A second deflecting means is provided to act upon the electron stream in opposition to the first deflecting means, and the sec-

ond deflecting means is energized in accordance with variations in the number of electrons acting upon the electron receiving means or anode, the arrangement being such that the stream is deflected to establish a state of equilibrium between the two deflecting means.

In all of the arrangements disclosed in the prior application the variation in the number of electrons received by the receiving means or anode establishes a variable potential in the anode circuit and this variable potential is utilized to energize the second deflecting means which acts in opposition to the first deflecting means.

In the arrangements disclosed herein, only one deflecting means is employed, and the variable effect which is to be relayed, amplified or translated controls the deflecting means to produce potential variations in the anode or output circuit, and a variable potential derived from the output circuit is utilized to oppose the variable effect acting on the deflecting means to thereby reduce the resultant deflecting action to a minimum. The action is such that for any given value of the applied deflecting effect, the electron beam will be deflected by an amount sufficient to establish an opposing effect which substantially balances the applied deflecting effect.

The present invention may be utilized in connection with a Wheatstone bridge to maintain the bridge in balance automatically and to provide a continuous indication of the amount of unbalance. The invention may also be employed as an instrument to measure and indicate mechanical forces, or as an instrument to measure and indicate the extent and direction of movement of an object.

Other aims and advantages of the invention will appear in the specification, when considered in connection with the accompanying drawing, wherein:

Fig. 1 is a circuit diagram showing one form of translating device according to the invention;

Fig. 2 is a circuit diagram showing another form of the invention applied to a Wheatstone bridge to maintain the bridge in balance and indicate the amount of unbalance; and

Fig. 3 is a diagram illustrating the invention applied to a force measuring and indicating arrangement.

In the arrangement shown in Fig. 1, there is diagrammatically represented a cathode-ray tube consisting of an insulating envelope 20. The internal construction of the cathode-ray tube may be of any suitable and well known type, but for the purpose of illustration, the tube has a source

of electrons represented by a heater or filament 21 for heating an electron emitting cathode 22. The electrons emitted by cathode 22 are accelerated and focused into an electron beam of suitable shape directed along the axis of the tube by means of an accelerating and concentrating electrode 23 mounted in the tube and maintained at positive potential with respect to the cathode 22 by means of a suitable source of potential, represented by the battery 24. The electron beam established within the tube is indicated by dotted lines 25.

Suitable electron receiving means, represented by the anode plates 26 and 27, are positioned within the tube to receive electrons from the beam 25. While two anode plates have been shown, it will be understood that only one plate may be employed if desired. The anodes 26 and 27 are connected through suitable coupling resistances 28 and 29 to a source of positive potential, represented by the battery 30, the negative terminal of which is connected to the positive terminal of battery 24. In some instances, the battery 30 may be omitted. Moreover, it is not essential that resistances 28 and 29 be connected to the battery 24, but they may be connected to ground. A load circuit or any other device 31 utilizing load current is connected across the leads to plates 26 and 27. An amplifier 32 may be included if desired.

The electron beam 25 may be initially concentrated or focused on either plate 26 or 27 or it may be focused to impinge upon both plates to an equal extent. In this example, the beam is deflected relative to both plates by means of a magnetic deflecting coil 32 which is energized from a suitable source of current 33 which may be a source of signalling currents or the currents may be derived from any variation of a factor which is to be measured. If desired, an amplifier 33a may be employed to amplify the current supplied to coil 32 from source 33. The coil 32 establishes a magnetic field transversely of the beam 25, whereby the beam is deflected in a direction depending upon the direction of the field established by the coil 32. Instead of using a coil for deflecting the beam, deflecting plates may be used if desired, see Fig. 2.

Deflection of the beam 25 in accordance with signals from the source 33 causes corresponding variations in the number of electrons impinging upon plates 26 and 27, thereby causing plates 26 and 27 to vary in potential in response to the signals from source 33. Where two plates are employed and the beam is initially positioned midway between the plates, the potential variations on plate 25 are opposite to the variations on plate 27, and the difference in potential between the plates supplies the load 31 with current which varies in accordance with the signals supplied from source 33. It will be understood that the load may be connected from either plate 26 or plate 27 to ground, or one of the plates may be omitted and the load connected between the remaining plate and ground.

A potentiometer 35 is connected to the load circuit for deriving from this circuit a potential to oppose the current supplied to the deflecting coil from the source 33. For this purpose, the output connection from potentiometer 35 is connected in shunt to a resistance 33b connected in series with the circuit which supplies current to the coil 32 from source 33. It will be understood that resistance 33b is not essential, and the currents from source 33 may be supplied to coil 32

through the connection to potentiometer 35. The connections from potentiometer 35 are such that the voltage or current supplied to the circuit of coil 32 is in opposition to the voltage or current supplied from source 33.

The operation of the arrangement shown in Fig. 1 is believed to be clear from the foregoing description. It is assumed that the field established by coil 32 tends to deflect the beam from mid-position toward the plate 26 and a potential difference is established between plates 26 and 27. The potential supplied from potentiometer 35 to the circuit of coil 32 opposes the current from source 33 and limits the amount of deflection of the beam 25. The beam 25 will be deflected by an amount sufficient to establish a substantial balance between the voltage from source 33 and the voltage from potentiometer 35. The voltage from potentiometer 35 does not exactly balance the voltage from source 33 because a certain unbalance is required to establish the necessary opposing voltage from potentiometer 35, but where the deflecting means is sufficiently sensitive, the opposing voltage will be substantially equal to the applied voltage. Under this condition, the potential difference existing between plates 26 and 27 will be directly proportional to the signal supplied from source 33. The proportion or ratio between the input signal and the signal supplied to the load may be adjusted or controlled by adjustment of the potentiometer 35.

A substantially linear relationship may be obtained between the output signal and the input signal by arranging the circuit constants so that the maximum output signal is obtained by a relatively small unbalance between the voltage impressed from source 33 and the voltage impressed from potentiometer 35. For example, the amount of unbalance required between these two control voltages to produce a maximum current or voltage in the load circuit may be of the order of one percent difference. In other words, the applied deflecting voltage or force should be greatly in excess of that required to produce maximum energy in the output circuit.

The arrangement represented in Fig. 2 is a variation of the arrangement shown in Fig. 1. In this arrangement, the beam is deflected by a pair of deflecting plates 36-37 instead of a coil, although a coil may be employed if desired. The variable effect which controls the deflection of the beam is a potential derived from the null circuit of a Wheatstone bridge formed by arms R1-R2-R3-R4, the bridge being energized from a suitable source represented by the battery 33c. The amplifier 33a may or may not be included between the Wheatstone bridge and the deflecting means as desired. The potential derived from potentiometer 35 is not applied to directly oppose the unbalance potential of the Wheatstone bridge, but it is applied to one or more arms of the bridge in a manner to reduce the amount of unbalance at any given time. The balancing voltage has been shown as applied across resistance R1 through switch 35a, but it may be connected across any other arm of the bridge, or across any pair of diagonal points, as may be found necessary to rebalance the bridge.

In using the arrangement shown in Fig. 2, one of the arms of the bridge will change in resistance according to some condition to be measured or indicated. For example, arm R1 may be a heat-sensitive resistance which changes

its value in response to temperature variations of a certain object, material or locality. Assume that the bridge is balanced and that no deflecting potential is applied to plates 36 and 37. Assume now that arm R1 increases in resistance by an amount equal to $\Delta R1$. This change in resistance will unbalance the bridge and cause the beam to be deflected so that a potential difference will be developed across anodes 26 and 27. This potential difference, after being amplified by amplifier 38 will be applied across arm R1 in a direction tending to rebalance the bridge. This action tends to reduce the potential applied to plates 36 and 37, and the deflection of the beam will be limited to an amount sufficient to substantially rebalance the bridge. The meter 31a connected across the output circuit will indicate the amount of unbalance caused by the resistance change $\Delta R1$ and will thus serve as an indirect indication of the temperature or other condition causing the change in resistance.

In Fig. 3, I have illustrated a form of my invention in which the deflecting means comprises a magnetic field which is mechanically moved with respect to the electron beam. The arrangement is adapted for the measurement of mechanical forces, and is suitable for use as a weighing device.

The movable field for deflecting the electron beam may be produced by an electromagnet, but in the example shown in Fig. 3, the field is produced by a permanent magnet 40 of the ring or horseshoe type mounted with its arms embracing the tube 20 so that the magnetic field between the poles of the magnet is positioned transversely of the electron beam 25. The magnet 40 is mounted at one end of a balancing lever 41 pivoted on a fulcrum 42 whereby the magnet 40 may be vertically moved with respect to the tube 20 by applying forces to the balancing lever. A weighing table 43 is carried by the lever 41 on the end opposite from the magnet 40, and a controlling force, a force to be measured, or an object 44 to be weighed, is applied to the table 43. An electromagnet having a winding 45 is energized from the output circuit and the movable armature or core 46 of the electromagnet is connected to the lever 41 and acts to oppose the movement of the lever 41 caused by the applied force or weight acting on the table 43.

In the operation of the arrangement shown in Fig. 3, a force or weight to be measured is applied to the table 43 and this causes magnet 40 to move upwardly with respect to the tube 20 and thus cause the beam 25 to shift and establish a potential difference between plates 26 and 27. This potential difference is amplified by amplifier 38 and energizes magnet winding 45 to oppose the upward movement of magnet 40 and thereby maintain the lever 41 in balance. Due to the opposing action of magnet 45-46 on lever 41, the lever will move a slight distance from its normal position under the action of the applied force, it being understood that only a slight movement of magnet 40 is required to produce a maximum potential difference between electrodes 26 and 27. The indicating meter 31a connected across the output circuit will provide an indication proportional to the weight or force applied against the plate 43.

The arrangement shown in Fig. 3 may also be used as a relay for controlling a device connected to the load circuit in response to a controlling force applied to balancing lever 41.

Obviously, the present invention is not restricted to the particular embodiments thereof herein shown and described.

What is claimed is:

1. An electronic translating device comprising, in combination, means for producing an electronic beam, input control means including means for deflecting said beam in accordance with signal variations, an output circuit including means controlled by said beam for establishing increasing amounts of energy flow in said output circuit with increasing deflection of said beam, and means variably energized from said output circuit and controlling said input deflecting means synchronously with said signal variations to limit the amount of deflection of said beam.
2. An electronic translating device comprising, in combination, means for producing an electronic beam, an input control means including means for deflecting said beam in accordance with signal variations, an output circuit including means controlled by the deflection of said beam for establishing increasing amounts of energy flow in said output circuit with increasing deflection of said beam, and means for supplying energy variations from said output circuit to said input deflecting means synchronously with said signal variations and in a direction to oppose the action of said deflecting means on said beam.
3. An electronic translating device comprising, in combination, means for producing an electronic beam, input control means including means for deflecting said beam in accordance with signal variations, an output circuit including means controlled by said beam for establishing increasing amounts of energy flow in said output circuit with increasing deflection of said beam, a source of input signals for energizing said deflecting means by a force greatly in excess of the force required to produce maximum energy output in output circuit, means variably energized from said output circuit and acting directly on said input control means for opposing said deflecting force by a substantially equal force varying synchronously with said signal variations, and means for indicating the magnitude of said opposing force.
4. An electronic translating device comprising, in combination, means for producing an electronic beam, an input circuit including means for deflecting said beam in response to variable signal energy supplied thereto, an output circuit including means controlled by the deflection of said beam for establishing increasing amounts of energy flow in said output circuit with increasing deflection of said beam, and a connection from said output circuit to said input circuit for variably energizing said input circuit synchronously with said signal energy variations and in opposition to said input energy.
5. An electronic translating device according to claim 4, including a Wheatstone bridge, said input circuit being energized from the null circuit of said bridge, and said connection supplying current to at least one arm of said bridge tending to maintain said bridge in balance.

HERBERT ZIEBOLZ.
